(57) **ABSTRACT**

A pair of scrub pants is provided having a built-in retention feature. The pair of scrub pants comprises two pant legs extending downward from a bottom side of a hip region and a waistband disposed on the top side of the hip region. One or more instrument retention features disposed on the waistband are accessible to the user. The one or more instrument retention features have a first position where one or more instrument retention features rest flat against the waistband. The instrument retention features can comprise one or more of elastic bands, hooks, snap fasteners, among others.

ENHANCED MEDICAL WEAR WITH BUILT-IN EQUIPMENT RETENTION FEATURES

DESCRIPTION OF RELATED ART

Medical scrubs were originally designed for use by surgeons and other medical personnel during operations in the operating room. Over time, the use of scrubs has increased throughout the hospital. Part of the reason for the proliferation of scrubs use throughout the hospital is the simple design without many embellishments, making scrubs easy to launder and cheap to replace if damages or stained irreparably.

The purpose of scrubs was to provide a simple design for clothing that can cover the individuals in the operating room to protect an individual's clothes not only from stains but also to reduce the places where contaminants to hide. Conventional scrubs (both scrub tops and scrub pants) include minimal features. Scrub pants are traditionally secured along the waistline by a draw string or elastic band. One or more pockets may be disposed on either or both legs.

SUMMARY

Various embodiments of the technology disclosed herein provides scrub pants with a built-in instrument retention feature. In various embodiments, the scrub pants comprise two pant legs extending downward from a bottom side of a hip region; a waistband disposed on a top side of the hip region; a draw string disposed on the waistband; and one or more instrument retention features disposed on the waistband, the one or more instrument retention features accessible to a user, wherein the instrument retention feature has a first position where the one or more instrument retention features rest flat against the waistband.

In various embodiment, the one or more instrument features comprises one or more elastic bands, wherein each of the one or more elastic bands are separate components. Each of the one or more elastic bands in various embodiments comprises a first end and a second end, each of the first end and the second end being attached to the waistband. In various embodiments, the first end and the second end of each of the one or more elastic bands are attached to an interior surface of the waistband. In some embodiments, the elastic band is woven into the waistband such that the first end enters the waistband through a first opening, the second end enters the waistband through a second opening, and the elastic band comprises a middle portion that is between the first opening and the second opening.

In other embodiments, the first end and the second end of each of the one or more elastic bands can be attached to an exterior surface of the waistband.

Attaching the first end and the second end to the interior and/or exterior of the waistband comprises one or more of sewn, glued, stapled, riveted, or heat sealed in various embodiments.

In various embodiments, the one or more elastic bands are portions of the same elastic band. In some embodiments, each of the portions of the same elastic band are associated with a region of the waistband, the region of the waistband enabling access to the portion of the same elastic band. In various embodiments, each of the regions of the waistband can include one or more attachment points to secure the portion of the same elastic band within the region of the waistband. The first end of the portion of the same elastic band within each region is attached to a first attachment

point of each region and a second end of the portion of the same elastic band within each region is attached to a second attachment point of each region in various embodiments.

In various embodiments, the one or more instrument retention features comprises one or more of elastic bands, hooks, snap fasteners, buckles, or a combination thereof.

In various embodiments, the one or more instrument retention features and the draw string are disposed in an interior of the waistband. In other embodiments, the one or more instrument retention features are disposed on a first section of the waistband and the draw string is disposed on a second section of the waistband. In various embodiments, the first section is disposed below the second portion.

BRIEF DESCRIPTION OF THE DRAWINGS

The present disclosure, in accordance with one or more various embodiments, is described in detail with reference to the following figures. The figures are provided for purposes of illustration only and merely depict typical or example embodiments.

FIG. 1 is an example scrubs pants in accordance with embodiments of the technology disclosed herein.

FIG. 2A is an example waistband with an example instrument retention feature in accordance with embodiments of the technology disclosed herein.

FIG. 2B is another example waistband with another example instrument retention feature in accordance with embodiments of the technology disclosed herein.

FIG. 2C is another example waistband with another example instrument retention feature in accordance with embodiments of the technology disclosed herein.

FIG. 2D is another example waistband with another example instrument retention feature in accordance with embodiments of the technology disclosed herein.

FIG. 2E is a front side of another example waistband with another example instrument retention feature in accordance with embodiments of the technology disclosed herein.

FIG. 2F is a back side of another example waistband with another example instrument retention feature in accordance with embodiments of the technology disclosed herein.

FIG. 2G is another example waistband with another example instrument retention feature in accordance with embodiments of the technology disclosed herein.

FIG. 3 is an example leg ends in a cinched position in accordance with embodiments of the technology disclosed herein.

FIG. 4 is an example scrub pants leg with an adjustment slit in accordance with embodiments of the technology disclosed herein.

FIG. 5 is an example of a leg end with multiple elastic sections in accordance with embodiments of the technology disclosed herein.

The figures are not exhaustive and do not limit the present disclosure to the precise form disclosed.

DETAILED DESCRIPTION

Because the initial intent for scrubs were to be used in an operating environment, the conventional design does not provide many functional features that would be desirable in other environments in the hospital outside of the operating room. Unlike in the operating room, instruments and other equipment tend to be carried by individuals while performing duties within other areas, such as the intensive care unit, patient rooms, or examination rooms. However, scrubs do

not have built-in features so that the person can retain these instruments in a safe and effective manner.

This lack of functionality increases the chances that tools are instruments are misplaced, lost outright, and/or contaminated during normal performance of duties. For example, in many cases individuals are required to carry instruments in one or both hands, such as stethoscopes. Because of this, when attempting to perform some action, such as adding information to a chart, the tool or instrument needs to be placed on some surface to free up the hands. This can cause the instrument to be misplaced. More importantly, this exposes the instrument to potential contamination from the surface upon which it is placed. Some instruments, like stethoscopes, can be laid across the individual's shoulders and behind the neck to free up the hands, but such methods of holding the instruments are not medically recommended for a number of reasons. The weight of the instruments can cause the shoulder muscles to tire over time sapping energy from the individual, which can lead to errors or accidents to occur. The movement of the instruments while contacting the individual's skin can also cause rashes or even cuts to form, which is an infectious disease issue (e.g., methicillin-resistant *Staphylococcus aureus* (MRSA) or other staph infections) that is unacceptable in a hospital environment. Having instruments hung around the neck also serve as a choking hazard, whether due to being caught on some obstruction or if dealing with a violent or out of control patient or individual. Finally, such a method of holding such instruments can cause damage to the instruments, either through the unintended position of the instrument or, depending on the material, deterioration of the material caused by the excess heat of contact with the skin.

Even where the scrub pants include pockets, there are many situations where the pockets are not suitable for storing the instrument or tool. Using a stethoscope as a non-limiting example, the shape and design causes the stethoscope to awkwardly rest in the pocket, increasing the chance that the stethoscope may catch on surfaces while moving. This not only poses a risk to the individual during motion but also poses a contamination risk. Such awkwardly placed instruments also are at risks of falling out of the pockets. For heavier instruments, like a stethoscope, the weight can also cause the pants to fall down from the waistline. The waistband of scrub pants must be maintained tight to the body to protect the individual from potential contaminants. Although the pants generally are secured by a draw string, elastic band, or a combination of both, the weight of some medical instruments are enough to cause waistlines that were originally secured at the proper height to sag and fall down because of the unexpected increase in the weight the draw string and/or elastic bands are trying to secure. The pockets are also not designed for such bulky instruments, resulting in the awkward positioning within the pocket to result in sagging of loose restraint of the instrument. Essentially, this loosely secured instrument functions like a limp body when being moved, flailing and moving around due to the motion that can cause the instrument to dislodge itself from the pocket.

Some clip-on or external additions to scrub pants or tops are known in the art. Clips that can be connected to the waistband of scrub pants have been used that are designed for holding specific types of instruments or tools. As an example, clip-on lanyards have been proposed that utilizes a roll of medical tape as a holster to retain a pair of shears or other small tool when attached to a scrub top or pant. Other clip-ons have been proposed specifically for stethoscopes that can clip onto the waistband of the pants, having

a molded element to secure the bell and ears of the stethoscope. Although such solutions can be used to add functionality to the conventional scrubs for retaining such instruments or tools, they still are additional components that need to be added to the scrubs themselves, making them susceptible to being lost. Such additional components also fail to address the issues caused by greater weight of some instruments, still causing the pants in some instances to fall lower down from the secure position around the waist because the securing mechanism (i.e., draw string, elastic band, or both) is not designed to include such components. Moreover, these types of peripheral components are specifically designed for different instruments, requiring that the individual either wears multiple additional components (adding weight and potentially interfering with movement). Although many external solutions, such as utility belts or other externally secured means known in other industries (e.g., armed forces, firefighting, law enforcement, etc.) these other fields work in environments with different operational constraints, making the bulky and heavier approaches in these fields poorly suited for the hospital.

Embodiments of the present disclosure provide a new functional design for medical wear, such as scrub pants, to overcome many of the drawbacks to conventional scrub pants discussed above. Due to the specific requirements imposed upon scrub pants from the nature of the environment in which they are worn, many approaches to carrying tools and instruments outside of the medical field fail to address the issues in a manner that ensures the scrub pants maintain their contamination-avoidance design. As discussed in greater detail below, the scrub pants of the present disclosure includes at least one built-in containment feature designed to allow for one or more instruments or tools to be securely held against the scrub pants to minimize the chance for contamination or lose without impacting the movements of the individual. Integrating the retainment feature within the scrub pant itself reduces the need for additional weight to be added through external, peripheral securing means or clips and works in concert with the waist securing features such that the retaining of instruments using the features of the enclosed embodiments does not impact the functionality of the scrub pants themselves. In other words, the instrument retainment features, being integrated directly into the design of the scrub pants, provides a simple method of instrument retainment in a cost effective manner that can still provide the necessary features of medical scrubs.

The embodiments disclosed herein shall be discussed and explained with respect to the various embodiments depicted in the accompany figures. Although a limited number of embodiments may be depicted, other embodiments may be described only textually, with reference made to one or more of the accompanying figures to provide context or explanation. Although not depicted, the scope of this disclosure covers those text-only disclosed embodiments equally with the explicitly depicted embodiments. A person of ordinary skill, reading the instant disclosure, would be sufficiently informed as to how the text-only embodiments can be implemented.

FIG. 1 illustrates an example pair of scrub pants 100 in accordance with embodiments of the present disclosure. The example scrub pants 100 are provided for illustrative purposes only and should not be interpreted as limiting the scope of the present disclosure to only the depicted embodiment. As shown in FIG. 1, the scrub pants 100 include two pant legs 101a, 101b (collectively, "pant legs 101" or "pant leg 101"), with a thigh pocket 102a, 102b (collectively, "thigh pockets 102" or "thigh pocket 102") disposed on each

of the pant legs **101a**, **101b**, respectively. In various embodiments, one or more thigh pockets **102** may be disposed on either or both of the pants legs **101**. In some embodiments, thigh pockets **102** may be disposed only on one of the pants legs **101**. Thigh pockets **102** can include a zipper or other fastening component to enable the thigh pocket **102** to be closed to secure items within.

The pant legs **101** can extend downward from a bottom side of a hip region **103**. The hip region **103** is the area of the scrub pants **101** covering the hip and pelvis of the human body. The hip region **103** can have a first hip side **103a** and a second hip side **103b** (collectively, "hip sides **103**" or "hip side **103**"), each hip side **103** extending in opposite directions from the center line C. In various embodiments, one or more hip pockets **104a**, **104b** (collectively, "hip pockets **104**" or "hip pocket **104**") may be disposed within the hip region **103**. As depicted in FIG. 1, hip pocket **104a** is disposed on a first hip side **103a** and hip pocket **104b** is disposed on the second hip side **103b**. In various embodiments, one or more of the hip pockets **104** may be segmented into one or more sub-pockets, with each of the sub-pockets having the same or different dimensions.

A waistband **105** is disposed on a top side of the hip region **103**. As depicted in FIG. 1, the waistband **105** may include a draw string **106** securing feature. In various embodiments, the draw string **106** can be threaded within the interior of the waistband **105**, with each end of the draw string **105** extending out of one or more eyelets **109** disposed on the waistband **105**. The one or more eyelets **109** enable the individual to pull on the ends of the draw string **106** to cinch the waistband **105** against the individual's waist. In various embodiments, each of the one or more eyelets **109** can comprise a hole within the waistband **105** that provides access to the interior of the waistband **105**. In some embodiments, the one or more eyelets **109** may be unadorned holes in the waistband **105**, while in other embodiments the one or more eyelets **109** may include a reinforcement element, such as a metal, plastic, or other rigid ring secured to the portion of the waistband **105** material forming the eyelet **109**.

An instrument retention feature **107** can also be included in the waistband **105**. As discussed above, conventional scrub pants comprise a simple design and do not provide features specifically designed to accommodate all types of medical instruments that are necessary while performing duties outside of the surgical space. The instrument retention feature **107** enables one or more different types of instruments **108** to be secured to the waistband **105**, providing low cost and efficient retention functionality built-in to the scrub pants **100** themselves. In the illustrated embodiment of FIG. 1, the instrument **108** is shown as a medical stethoscope, but this should not be interpreted as limiting the scope of the technology disclosed in the present disclosure. The instrument retention feature **107** can be used to retain a plurality of other medical instruments and tools, including medical shears, pagers, reflex hammers, among others.

FIGS. 2A-2F illustrate various example instrument retention features **107** in accordance with the technology disclosed herein. Wherever common reference numerals are used across a number of different drawings, any description of the element so referenced should be interpreted to apply to every instance of the element across the various drawings, unless expressly specified otherwise. Where one or more other figures are referenced with respect to one or more elements shown in a specific figure as being "similar to," "as discussed above," "in a like manner," or other type of referential term or phrase, the disclosure associated with the

element or elements there referenced apply equally to the specific figure unless otherwise stated. A plurality of example embodiments of the instrument retention features **107** are shown in FIGS. 2A-2F, but the scope of the technology disclosed herein should not be interpreted as limited only to the depicted embodiments, and encompasses other types of instrument retention features **107** similar to those disclosed herein.

As illustrated in FIG. 2A, the instrument retention feature **107a** can comprise an elastic band **202**. As depicted, the elastic band **202** can include a first end **204a** and a second end **204b** (collectively, "ends **204**" or "end **204**"). In various embodiments, each of the ends **204** can be sewn into the material of the waistband **105** such that the elastic band **202** is built into the waistband **105** and extends over a portion of the circumference of the waistband **105**. In various embodiments, the ends **204** may be built into the waistband **105** in various ways, including but not limited to, sewing, glued, heat-welded, stapled, pinned, riveted, or otherwise secured to the material. As illustrated in FIG. 2A, the ends **204** are shown as being secured on the interior of the waistband **105** as represented by the broken lines **205**. That is, the elastic band **202** is woven into the waistband **105** in one or more locations, with the first end **204a** is within an interior of the waistband and exits the waistband at an opening so that the elastic band **202** extends over the exterior surface of the waistband **105**, and the second end reenters the interior of the waistband **105** through a second opening. As arranged, the elastic band **202** comprises a middle portion exposed to a user and positioned parallel to the exterior surface of the waistband **105**, the middle portion defined as the portion of the elastic band **202** between the first end **204a** and the second end **204b**. In various embodiments, the middle portion could be defined as the portion of the elastic band **202** defined as the portion between the first opening closest to the first end **204a** and the second opening closest to the second end **204b**. In some embodiments, the ends **204** may be secured to the exterior surface of the waistband **105**. When in a non-stressed position, the elastic band **202** can be configured to rest flat against the waistband **105**. In various embodiments, the elastic band **202** can be attached to the waistband **105** such that the ends **204** of the elastic band **202** are secured on the exterior surface of the waistband **105**. In other embodiments, the ends **204** may be inserted into an interior void of the waistband **105** through one or more openings (not shown in FIG. 2A) and secured on the interior surface of the waistband **105**. The elastic band **202** can include one or more types of materials having an elastic quality commonly used in the fashion industry. In various embodiments, the first end **204a** and the second end **204b** may be positioned such that the elastic band **202** extends all or substantially all of the entire circumference of the waistband **105**, forming a circular elastic band **202**. That is, the elastic band **202** can extend from the first end **204a**, around the rear of the waistband **105**, to the second end **204b**.

Although the term "flat" is used to refer to the non-stressed position of the elastic band **202**, a person of ordinary skill in the art would understand that, when worn by an individual, the waistband **105** and, therefore, the elastic band **202** would deform according to the shape of the individual's body, and would understand that the descriptor "flat" is considered from the relationship of the elastic band **202** to the waistband **105** without considering and curvature or other differences in shape caused by the body. Moreover, a person of ordinary skill in the art would understand that "flat" as used herein does not require that the waistband

material 105 be smoothed out and free of all ridges, folds, or other orientations of the material of the waistband 105.

When an instrument needs to be carried, the user can grab the elastic band 202 and stretch the elastic band 202 into a stressed position such that a void is created between the elastic band 202 and the waistband 105, into which the instrument may be inserted. Once inserted, the elastic band 202 can be relaxed and returned back to the non-stressed position, thereby securing retaining the instrument (e.g., a stethoscope, shears, etc.) against the waistband 105. In this way instruments and/or tools needed by the individual can be securely retained without the need for peripheral components, eliminating cost. Moreover, because the elastic band 202 is built into the waistband 105, the weight of the instrument has less impact on the proper placement of the waistband 105 once secured using the draw string 106. When using external peripheral components, like clip-on solutions, the integrity of the closure of the waistband 105 against the individual's body is compromised, creating space such that the external component can be attached, which can necessitate either that the draw string 106 is readjusted. This can be inconvenient to the user as well as exposing the user to potential discomfort from having another object be tightly pushed against the person's body (because of the need to ensure the waistband 105 is tight against the body to keep the waistband 105 in place). The elastic band 202 does not comprise the integrity of the contact between the waistband 105 and the person's body, thereby reducing the chance that the waistband 105 may fall or sag.

In various embodiments, the instrument retainment feature 107 can comprise one or more hooks 206, as depicted by the example embodiment 107b illustrated in FIG. 2B. The example hooks 206 can provide a connection point for one or more instruments or tools having a compatible securing structure disposed thereon. Non-limiting examples of a compatible securing structure includes handles, eyelets, indentations or protrusions creating a void within which one or more hooks 206 can interface, among other structures. In various embodiments, the securing structure disposed on the instrument or tool can be designed to interface with the hooks 206, while in other embodiments the securing structure can comprise a structure that is part of the instrument or tool but was not designed specifically to interface with the hooks 206. The hooks 206 can be built into the waistband 105 in a similar manner and using similar means as discussed above with respect to the elastic band 202. In some embodiments, a rear portion 208 of one or more hooks 206 can be secured to the waistband 105 within an interior of the waistband 105, as shown by the broken line, the rear portion 208 entering the waistband 105 through an opening 210 in the waistband 105 (as shown by the broken lines in FIG. 2B). In some embodiments, the hooks 206 may be secured to the exterior surface of the waistband 105. In some embodiments, the waistband 105 can include one or more hook attachment features (not shown in FIG. 2B) designed to allow the user to attach a hook 206 to the waistband 105. In such embodiments, the hook attachment feature is built into the waistband 105, with the hooks 206 being attachable and detachable from the waistband 105. The hooks 206 can comprise one or more materials, including but not limited to plastic, metal, ceramic, or a combination thereof. In some embodiments, the hooks 206 can be rigid, maintaining a single shape, while in other embodiments the hooks 206 can comprise a flexible material configured to allow the hook 206 to be moved into one or more shapes and maintain the shape in which it is moved.

In some other embodiments, the instrument retainment feature 107 can comprise a buckle 212, such as the example instrument retainment feature 107c depicted in FIG. 2C. For ease of discussion, the buckle 212 depicted in FIG. 2C is depicted as a side release buckle, but that should not be interpreted to limit the buckle 212 to only this type of buckle. In various embodiments, the buckle 212 can comprise any type of buckle or clasp. As shown in FIG. 2C, the buckle 212 comprises a first portion 214 and a second portion 216. In various embodiments, the first portion 214 can comprise a strap 214a having a first end 218a and a second end 218b. In various embodiments, a catch component 220a may be disposed on the second end 218b of the strap 214a. The catch component 220a is one side of the securing component forming the buckle 212, the catch component 220a comprising the fastener portion (e.g., hook, pin, seat belt tongue, etc.) that is inserted into or otherwise coupled to the receiver component 222. FIG. 2C illustrates the catch component 220a (i.e., the side release buckle tongue) coupled to the receiver component 220b by inserted the catch component 220a into an interior space of the receiver component 220b through an opening of the receiver component 220b. The second portion 216 can comprise a strap 216a having a first end 222a and a second end 222b. In various embodiments, the receiver component 220b may be moveably coupled to the strap 216a, with the second end 222b of the strap 216a inserted within a slot disposed on a rear of the receiver component 220b such that the second end 222b of the strap 216a is wrapped around the slot and can extend towards the first end 222a. The receiver component 220b is moveable along the length of the strap 216a defined by the first end 222a and the second end 222b.

Although the first portion 214 is disclosed as having the catch component 220a disposed thereon, and the second portion 216 is disclosed as having the receiver component 220b, this is provided for example purposes only. In various embodiments, the receiver component 220b may be disposed on the first portion 214 and the catch component 220a may be disposed on the second portion 216. When an instrument or tool needs to be secured, the instrument or tool can be placed against the waistband 105 and the catch component 220a is inserted into the receiver component 220b. To retain the instrument or tool, the second end 222b of the strap 216a can be pulled such that more of the strap 216a is pulled through the slot to move the receiver component 220b in a direction towards the first end 222a of the strap 216, tightening the buckle 212 against the instrument or tool, in turn tightening the instrument or tool against the waistband 105 to secure the instrument or tool against the person.

FIG. 2D illustrates another example instrument retainment feature 107d in accordance with embodiments of the technology of the present disclosure. As depicted, the instrument retainment feature 107d comprises one or more snap fasteners 230. The snap fasteners 230 can be configured to couple with a corresponding disc disposed on the instrument or tool. The snap fasteners 230 can be built into the waistband 105 in a similar manner as discussed above with respect to the elastic band 202 of FIG. 2A.

In various embodiments, more than one instrument retainment feature 107 can be disposed along the circumference of the waistband 105. FIGS. 2E and 2F illustrates an example embodiment wherein multiple instrument retainment features 107 are disposed along the circumference of the waistband 105 in accordance with the technology disclosed herein. FIG. 2E illustrates a front side 280 of the scrub pants and FIG. 2F illustrates a back side 290 of the scrub pants. As

depicted in FIGS. 2E and 2F, there are several regions 240, each having an instrument retainment feature 107 disposed therein. In the illustrated embodiment, each of the regions 240 include an elastic band-type instrument retainment feature, similar to the elastic band 202 discussed with respect to FIG. 2A above. In some embodiments, each elastic band 202a-202n can be a separate elastic band component (as shown in FIG. 2A), while in other embodiments each elastic band 202a-202n may be different portions of the same elastic band 202 extending around all or substantial all of the circumference of the waistband 105 (as shown in FIGS. 2E and 2F), wherein each region 240 represents an opening in the waistband 105 that enables the person to interface with the portion of the elastic band 202 within the region 240 to move the portion 202a-202n to either a stressed or destressed position (as discussed above with respect to FIG. 2A). In some embodiments, each region 240 may include one or more attachment points, such as attachment points 242a and 242b of region 240f. In such embodiments, the attachment points 242a and 242b serve to secure the portion of the elastic band 202f within the region 240f, thereby ensuring that interacting with any of the other portions 202a-202n does not interfere with the portion 202f. In such embodiments, the first end 244a of the elastic band portion 202f is attached to the first attachment point 242a and the second end of the elastic band portion 202f is attached to the second attachment point 242b. Accordingly, if an instrument or tool is retained within the portion 202f, movement or use of another portion (e.g., portion 202c in region 240c) does not cause any movement or change in the positioning of the portion 202f. In some embodiments, adjacent regions 240 may share the same attachment point 242 such that an end of the elastic band portions in the adjacent regions 240 are secured at the same attachment point 242. In various embodiments, the elastic band-type retainment feature may go around substantially all of the circumference of the waistband 105. In the present disclosure, "substantially all" comprises an elastic band-type instrument retainment feature extending from a first end secured next to a first eyelet of the drawstring 106 to a second end secured next to a second eyelet of the drawstring 106.

Although FIG. 2E discusses multiple regions 240 with respect to elastic band-type instrument retainment features 107, such discussion is applicable to other embodiments, such as the embodiments discussed with respect to FIGS. 2B-2D. Moreover, although discussed as separate embodiments, one or more types of instrument retainment features 107 can be combined in various embodiments. In various embodiments, at least one region 240 can include a different instrument retainment feature from one or more regions. In various embodiments, the type of instrument retainment feature discussed with respect to FIGS. 2E and 2F can be the drawstring 106 itself. In such embodiments, the drawstring 106 can weave in and out of the waistband 105 through one or more openings (similar to the openings discussed with respect to the elastic band 202, the hooks 206, and the buckle 212 discussed above with respect to FIGS. 2A-2C) within the regions 240 in a similar manner as the elastic band portions discussed with respect to FIGS. 2E and 2F. Utilizing the drawstring 106 as both the means for maintaining the level of the waistband 105 on the person's body and as the retaining means for an instrument or tool (e.g., a stethoscope). The instrument or tool can be secured in a similar manner as that discussed above with respect to the elastic band 202 of FIG. 2A, where the drawstring portion exposed within a region 240 (i.e., exits the waistband 105 through a

first opening and reenters the waistband 105 through a second opening) can be extended into a stressed position by the person to create a space between the drawstring portion and the waistband 105 surface and the instrument or tool can be entered into the space. When the drawstring portion within the region 240 is returned to a non-stressed position, the drawstring portion in the region exerts a force against the instrument or tool to retain the instrument or tool against the person's body, while also serving to maintain the level of the waistband 105.

Referring to FIG. 1, the instrument retainment features 107 discussed above may be disposed in the same plane as the draw string 106, as shown in FIGS. 1-2F. In various embodiments, the instrument retainment features 107 and the draw string 106 may be disposed within the same interior of the waistband 105, while in other embodiments the waistband 105 may have a first interior associated with the instrument retainment features 107 and a second interior associated with the draw string 106 so that the instrument retainment features 107 and the draw string 106 are separated by a middle wall of the waistband 105. In some embodiments, the instrument retainment features 107 may be positioned above or below the draw string 106. In such embodiments, the waistband 105a can comprise two sections 250a and 250b (collectively, "sections 250" or "section 250") as depicted in the example waistband 105a of FIG. 2G. As shown, each section 250 can be associated with one of the instrument retainment features 107 or the draw string 106. In some embodiments, section 250a can be associated with the draw string 106 (i.e., the draw string 106 is disposed within the section 250a) and section 250b can be associated with the instrument retainment features 107. In other embodiments, the association of the sections 250 may be reversed. Separating the waistband 105 into two sections 35 enables the instrument retainment features 107 to be positioned along the person's waist in a more effective manner. As a non-limiting example, a stethoscope might be more comfortably secured if the instrument retainment feature 107 is positioned lower than the draw string 106 used to secure the scrub pants to the person's waist.

Referring to FIG. 1, the scrub pants 100 can include a pant leg adjuster 110a and 110b (collectively, "pant leg adjusters 110") disposed on a leg end 112a and 112b (collectively, "leg ends 112"), respectively. The pant leg adjusters 100 enable the person to adjust the form and function of the bottom of each pant leg (i.e., the leg ends 112), allowing the leg ends 112 to be in a relaxed position (i.e., non-adjusted), a cinched position, or any intermediate position between the relaxed position (as depicted in FIG. 1) and the cinched position (as depicted in FIG. 3). The example leg ends 302a and 302b illustrate the cinched position, whereby the leg ends 302a and 302b are reduced in circumference relative to the circumference of the remainder of leg portion 304a and 304b. In various embodiments, the pant leg adjusters 110 can comprise a leg drawstring 114. The leg drawstring 114 can have a toggle disposed on the end, the ends of the leg drawstring 114 being routed through an opening in the toggle and the toggle. In the rest state, the toggle is kept in place by a stopper inside the opening of the toggle exerting a force against the ends of the leg drawstring 114 to push the ends of the leg drawstring 114 against an interior surface of the opening. To adjust the position of the leg ends 112 a button on the toggle can be depressed, thereby releasing the pressure exerted by the stopper and allowing the toggle to move along the length of the ends of the leg drawstring 114.

As seen in FIG. 3, when in the cinched position the material in the leg portion 304a and 304b can billow over or

11

bunch up above the leg ends 302a and 302b. In some embodiments, an adjustment slit can be included in the leg ends. FIG. 4 illustrates example leg 400 in accordance with the technology of the present disclosure. As shown in FIG. 4, the leg 400 can include an adjustment slit 402 extending through the leg end 404 and into the leg portion 406. The adjustment slit 402 reduces the amount of material of the leg portion 406 that needs to be compressed when the leg end 404 is moved from the rest state to the cinched state. In various embodiments, the adjustment slit 402 may have a backing swatch (not shown in FIG. 4) disposed on the inside of the leg portion 406 and/or the leg end 404 and extending across the width of the adjustment slit 402 to cover the person's leg when the leg end 404 is in the rest state. In various embodiments, the backing swatch can comprise a different material from the material comprising the leg material. In other embodiments, the slit 402 may not have a backing swatch, and when in the rest position the person's leg is exposed to the air.

The leg end 404 depicted in FIG. 4 comprises elastic material (represented by the vertical lines). In various embodiments, the entire leg end 404 may comprise an elastic material. In other embodiments, one or more portions of the leg end 404 may comprise elastic material. FIG. 5 illustrates an example leg end 500 comprise a first side 502a and a second side 502b in accordance with embodiments of the technology disclosed herein. As shown in FIG. 5, the leg end 500 comprises a non-elastic section 506 having a first elastic section 504a connected to a first end and a second elastic section 504b connected on a second end. By having the elastic material 504 only used in certain sections of the leg end 500 the bunching effect when the leg end 500 is cinched is further reduced because such bunching is less to occur in the non-elastic sections. In some embodiments, the leg end 500 may further include a slit similar to the slit 402 discussed with respect to FIG. 4 above.

As used herein, the term "or" may be construed in either an inclusive or exclusive sense. Moreover, the description of resources, operations, or structures in the singular shall not be read to exclude the plural. Conditional language, such as, among others, "can," "could," "might," or "may," unless specifically stated otherwise, or otherwise understood within the context as used, is generally intended to convey that certain embodiments include, while other embodiments do not include, certain features, elements and/or steps.

Terms and phrases used in this document, and variations thereof, unless otherwise expressly stated, should be construed as open ended as opposed to limiting. Adjectives such as "conventional," "traditional," "normal," "standard," "known," and terms of similar meaning should not be construed as limiting the item described to a given time period or to an item available as of a given time, but instead should be read to encompass conventional, traditional, normal, or standard technologies that may be available or known now or at any time in the future. The presence of broadening words and phrases such as "one or more," "at least," "but not limited to" or other like phrases in some instances shall not be read to mean that the narrower case is intended or required in instances where such broadening phrases may be absent.

What is claimed is:

1. A scrub pants comprising:
two pant legs extending downward from a bottom side of a hip region;
a waistband disposed on a top side of the hip region;
a drawstring disposed in the waistband to adjust a circumference of the waistband; and

12

an instrument retention feature disposed on the waistband, the instrument retention feature including an elastic band having a first end, a middle, and a second end, and a boundary of the middle being defined at least in part by a first circumferential edge and a second circumferential edge disposed opposite the first circumferential edge,

wherein each of the first end and the second end of the elastic band are fixedly attached to the waistband via at least one of sewing, gluing, stapling, riveting, or heat sealing,

wherein the first circumferential edge and the second circumferential edge of the elastic band each extend in a direction along a circumference of the waistband from the first end on the waistband to the second end on the waistband such that at least a portion of the first circumferential edge and at least a portion of the second circumferential edge of the elastic band, between the first end and the second end, are unattached from the waistband and the scrub pants,

wherein the elastic band extends elastically externally away from the scrub pants, whereby a void is defined between:

an inner-facing surface of the elastic band and an outer-facing surface of the waistband, and
the first end and the second end, and

wherein the void extends unobstructed beyond both the first circumferential edge and the second circumferential edge of the elastic band such that when an instrument is retained by the instrument retention feature, a portion of the instrument rests against an outer surface of a pant leg of the two pant legs.

2. The scrub pants of claim 1, wherein the elastic band of the instrument retention feature is a first elastic band of a first instrument retention feature, and

wherein the scrub pants further comprise a second instrument retention feature including a second elastic band that extends in the direction of the circumference of the waistband from a third end on the waistband to a fourth end on the waistband such that at least a portion of a middle of the second elastic band between the third end and the fourth end is unattached from the waistband and extends externally away from the scrub pants.

3. The scrub pants of claim 2, wherein the first elastic is separate from the second elastic band.

4. The scrub pants of claim 1, wherein the drawstring extends around the waistband in a passage, and
wherein the first end and the second end of the elastic are attached to an interior surface of the passage in the waistband without interfering with the drawstring.

5. The scrub pants of claim 1, wherein the elastic band is attached to an exterior surface of the waistband at a first position and a second position.

6. A lower-body garment comprising:
a waistband;
leg portions extending from the waistband;
a drawstring disposed in the waistband to provide adjustability of a size of the waistband; and
an elastic band having a first end, a middle, and a second end, and a boundary of the middle being defined at least in part by a first circumferential edge and a second circumferential edge disposed opposite the first circumferential edge,

wherein each of the first end and the second end of the elastic band are fixedly attached to the waistband via at least one of sewing, gluing, stapling, riveting, or heat sealing,

13

wherein the first circumferential edge and the second circumferential edge of the elastic band each extend in a direction along a circumference of the waistband from the first end on the waistband to the second end on the waistband such that at least a portion of the first circumferential edge and at least a portion of the second circumferential edge of the elastic band, between the first end and the second end, are unattached from the waistband and the lower-body garment,
 wherein the elastic band extends elastically externally away from the lower-body garment, a void is defined between:
 an inner-facing surface of the elastic band and an outer-facing surface of the waistband, and
 the first end and the second end, and
 wherein the void extends unobstructed beyond both the first circumferential edge and the second circumferential edge of the elastic band such that when an instrument is retained by the elastic band, a portion of the instrument rests against an outer surface of a leg portion of the leg portions.

7. The lower-body garment according to claim 6, wherein the elastic band is sewn to the waistband.

14

8. The lower-body garment according to claim 6, wherein the elastic band is disposed at a front side of the waistband that is offset from a center-body region of the waistband.
9. The lower-body garment according to claim 6, wherein the drawstring extends outward from a front side of the waistband at a center-body region of the waistband, the drawstring extending from inside the waistband via eyelets.
10. The lower-body garment according to claim 6, wherein the elastic band includes two elastic bands, each elastic band being respectively positioned opposite each other, offset from a center-body region of the waistband.
11. The lower-body garment according to claim 6, wherein the leg portions include pockets.
12. The lower-body garment according to claim 6, wherein the portion of the elastic band between the first end and the second end is sized to accommodate a folded stethoscope therethrough.
13. The lower-body garment according to claim 6, wherein the void has a width to accommodate a folded stethoscope therethrough.
